SWINGING-TRAY CONVEYER

Jacob F. Savel and Harry Feige, Saginaw, Mich.,
assignors to Baker Perkins Company, Inc.,
Saginaw, Mich., a corporation of New York

Application April 20, 1933, Serial No. 666,963

4 Claims. (Cl. 198—158)

This invention pertains to chain conveyer systems of the swinging tray type wherein trays are pivotally suspended between two parallel chains, and in which the principal runs or flights are horizontal. It relates more particularly to a novel sprocket structure employed at the end of a conveyer flight where the travel of the conveyer is changed and the trays pass into another flight above or below that just traversed.

10 In conveyers of the type referred to, two sprockets, one for each of the parallel conveyer chains, are fixed to a transverse axle shaft. Heretofore circular sprockets have been used, each having four pintle pockets spaced apart circumferentially. 15 These circular sprockets imposed certain undesirable limitations upon the dimensions of the trays and their spacing from each other. These limitations have necessitated relatively wide gaps between the edges of adjacent trays in the horizontal runs. In all conveyers of this type these gaps require an overall length out of proportion to the dimensions of the trays and the capacity 20 of the conveyer.

In bake ovens in particular these gaps permitted 25 hot gases from the bottom of the oven to flow between the trays, which resulted in excessive browning of the loaf surfaces adjacent to the tray edges. In addition this flow of hot gas between the trays has prevented the precise control of the top and bottom heat desired for baking certain 30 kind of goods.

Since the edges of the trays must clear the sprocket shaft as they pass around the sprockets, the maximum permissible width of a tray equals 35 the pitch diameter of the sprocket, less the diameter of the shaft, and less a small clearance margin. When truly circular sprockets were used, the length of the circumferential arc between two consecutive pintle pockets, and hence the 40 chain length between the tray pintles, was considerably greater than the maximum tray width as determined by the limitations noted above. Therefore, with horizontal runs the gaps between trays were wider than was required for operating 45 clearances, and they could not be reduced by widening the trays, for the reasons stated.

It has long been desired in tray ovens of this kind to reduce as much as possible the gaps between successive trays, in order to overcome the 50 difficulty.

It is an object of the present invention, by a simple change in design of the conveyer sprockets, to minimize the gaps between trays and without interfering with the free passage of the trays 55 around the sprocket shaft. By thus reducing the

gaps we insure more even baking and better heat control in bake ovens employing swinging tray conveyers, and in ovens, proofers and other conveyers of this kind we effect a substantial reduction in the overall length of a conveyer having 60 a given number of trays, or conversely, make possible the addition of trays to a conveyer of, a given length.

The invention consists primarily of a novel sprocket in combination with a conveyer chain of 65 a swinging tray conveyer having horizontal runs. The sprocket has a plurality of pintle pockets to receive those rollers of the chain which carry the tray pintles, the periphery of the pockets being 70 cut away between successive pintle pockets so that the peripheral distance between them is less than the distance along the arc of the pitch circle of the pintle pockets.

The shortened peripheral sections between the 75 pintle pockets may be flattened arcs, or they may be straight, and may have teeth to engage the chain, or may be toothless and smooth.

With the foregoing and certain other objects in 80 view, which will appear later in the specification, our invention comprises the devices described and claimed and the equivalents thereof.

In the drawing Fig. 1 is a side elevation of one embodiment of our improved sprocket as it is employed in a bake oven conveyer of the single lap type wherein the swinging tray conveyer travels through two horizontal flights, or runs.

Figs. 2 and 3 are side elevations showing alternative forms of the novel sprocket.

In Fig. 1, numeral 1 designates the baking 90 chamber in which is installed a conveyer consisting of chains 2 (one of which is shown) traveling on horizontal tracks 3. The tray pintles or rollers 4 carry the pivotally suspended trays 5, of known type. An axle shaft 6 extending transversely across the oven carries sprocket 7 95 for the conveyer chain.

The sprocket 7 has four pintle pockets 8, which receive the pintles 4 of the conveyer chain. The 100 arcuate peripheral section 9 (indicated by the broken line) of the sprocket between two pintle pockets is flatter than the corresponding arc of the circle determined by the pintle pockets. Accordingly the path of the chain along flattened arc 9 between the successive pintle pockets 8 is shorter than the corresponding distance around the periphery of a circular sprocket of equal radius at the pintle pockets. Thus the improved sprocket permits the use of shorter lengths of chain between adjacent trays, and the gaps 110

between the trays 5 on the horizontal tracks 3 are minimized.

The sprocket 7, like the circular sprockets previously used, limits the maximum width of the 5 trays 5 to substantially the diameter of the sprocket minus the diameter of the shaft 6 and minus the clearance necessary to allow free 10 passage of the trays around the shaft. Using the improved sprockets, flattened between pintle 15 pockets as described, the width of the gaps between successive trays in horizontal runs needs be only twice the clearance C required between the edge of a tray 5 and the sprocket shaft 6.

Fig. 2 shows a sprocket 17 made according to 15 the invention which has three pintle pockets 18 spaced one hundred twenty degrees apart. The sprocket is toothed similarly to that shown in Fig. 1, with pockets between the teeth to receive the rollers of the chain 2 intermediate the 20 tray pintles 4.

In the forms illustrated in Figs. 1 and 2 we 25 have shown the flattened sprocket periphery slightly curved between successive pintle pockets 8, in order to accommodate the links of certain standard chains available in the market. It is within the scope of the invention as claimed to have these peripheral sections straight instead of curved.

Fig. 3 illustrates an embodiment of the last 30 named form of the invention. A five-sided sprocket 27 having five pintle pockets 28 carries the conveyer chain 2. The peripheral sections 29 of the sprocket between the pintle pockets are toothless and flat so that the chain on the sprocket 35 between the pintles lies in substantially a straight line. The peripheral section 29 may also be slightly concave or recessed with respect to the pintle pockets 28 so that only the pintles will engage the sprocket. Such variations in 40 sprocket form are within the scope of the appended claims.

Having thus described our invention, what we 45 claim and desire to secure by Letters Patent is:

1. In a chain conveyer system of the swinging-

80 tray type which carries the trays through horizontal flights, a chain sprocket having a plurality of pintle pockets, and having those parts of its periphery between successive pockets flattened so that the path between them assumed by the chain is shorter than the corresponding path along the pitch circle of the pintle-pockets.

2. In a bake-oven conveyer system having a 85 pair of parallel chains carrying swinging trays between them through horizontal flights, chain sprockets spaced apart on a horizontal axle shaft and having each a plurality of pintle-pockets, the periphery of each sprocket between successive pintle pockets being shorter than the corresponding 90 arc of the pitch circle of the pintle-pockets, whereby short lengths of chain between successive trays may be employed and the width of the gaps between the edges of successive trays in the horizontal flights is minimized.

3. In traveling chain conveyers carrying swinging 95 trays through horizontal flights, a chain sprocket having four pintle pockets spaced about its circumference and having its periphery flattened between said pintle pockets to permit the use of lengths of chain between adjacent trays 100 shorter than the distance between pockets along the pitch circle of the pintle pockets whereby the width of the gaps between the edges of successive trays in the horizontal flights is minimized.

4. In a chain conveyer system of the swinging-tray type, in combination, a chain having tray pintles located at non-adjacent pivots, one or more pivots which do not carry trays between the consecutive pintles, and a chain sprocket 110 therefor having a plurality of pintle pockets and having flattened chain-supporting peripheral portions between successive pintle pockets, whereby the lengths of chain between successive tray 115 pintles may be shorter than the arcuate path along the pitch circle of said pintle pockets.
